UNITED STATES PATENT OFFICE

EMIL F. ZUBER AND FREDERICK A. DOWLING, OF PEORIA, ILLINOIS, ASSIGNEES TO THE
MICHIGAN SILO COMPANY, OF KALAMAZOO, MICHIGAN

SILO DOOR

Application filed March 11, 1929. Serial No. 345,917.

This invention relates to the art of silos and particularly to silo door structures. It has for its primary object the provision of means for effectively closing and sealing a door opening in a silo in a form that may be easily handled and set in place or removed.

Further objects reside in the provision of a door clamping device which will permit the door to be employed without change in silos having steel, wood, or concrete staves; in a clamping device of an adjustable nature; and in the unique structure of a clamping device that will also serve as a step or rung in a ladder on the silo.

Other objects will become readily apparent to those versed in the art from the following description of one particular form of the invention in reference to the accompanying drawing, in which—

Fig. 1 is a fragmentary elevation of a silo embodying the invention;

Fig. 2, a front elevation of a door;

Fig. 3, a top plan view of the door;

Fig. 4, a vertical elevation on the line 4—4 in Fig. 3;

Fig. 5, a vertical elevation on the line 5—5 in Fig. 3; and

Fig. 6, a vertical section on the line 6—6 in Fig. 4.

Like characters of reference indicate like parts throughout the several views.

We form a door 10 of sufficient height and width to lap over the edges of the door opening 11 in the silo 12. Around the edge of the door 10 on its forward face, is secured a compressible ribbon of felt 13.

On substantially the horizontal center line of the door 10, we mount the brackets 14 and 15 near the felt 13 but sufficiently removed therefrom to permit the door 10 to be brought up from the inside against the vertical staves 25 and 16 of the silo 12 so that the brackets 14 and 15 may project forwardly therebetween without striking the side staves.

These brackets 14 and 15 each have a low base and a forward frusto-conical head with a shoulder 17 therearound at the base of the head. The head is bored centrally and horizontally therethrough by a hole reduced in diameter from that of the inside of the

base. A bolt 18 has a coiled compression spring 19 slipped over it and the bolt is entered and extended through the hole from the rear side to bring the spring 19 to bear compressively between the rear side of the base of the head and the forward side of the head of the bolt.

A clamp lever 20 is provided with a boss 21 toward one end having an integral inverted frusto-conical bore entering and adapted to receive the conical bracket head therein, the rear face of the boss 21 being adapted to contact and bear against the shoulder 17 when the two conical surfaces meet in a sliding fit. The bolt 18 extends through the boss 21 and beyond the forward face of the lever 20 as a means of retaining the lever 20 on the bracket. By adjustment of the nut 22, the pressure between the lever 20 and the bracket is varied accordingly. The bolt 18 passes through both the lever 20 and the bracket with a loose fit.

By the foregoing description, it may be seen that the lever 20 may be rocked around the bracket 14 or 15, as the case may be, in a vertical plane parallel to the face of the door. The outer end of the lever 20 is provided with a flat plate 26 having out-turned ears 27 and 28. Midway between the brackets 14 and 15 on the vertical center line of the door 10, we mount the stop bracket 29 which has a face curving outwardly, around and downwardly from the door 10, over which the inner ends of both levers 20 may slide and be guided to enter behind the ear 30 carried on the bracket 29, where the two levers 20 may rest and are held against further downward travel in a horizontal line Figs. 1, 2 and 3.

To position the door 10 in the silo, the levers 20 are rocked upwardly to the positions as indicated by dash lines in Fig. 2. The levers 20 will remain at these or any other positions where left by reason of the springs 19 pulling the levers into compressive frictional engagement with the brackets 14 and 15. The center bracket 29 serves as a convenient handle in bringing the door 10 up against the rear sides of the staves 25 and 16 and intermediate spacing bars 32 and holding it there. The levers 20 are then pulled down, one at a

time to bring the plate 26 of each around and on the outer faces of the staves, the horizontal distance between the plates 26 and the door 10 being normally less than the thickness of the staves.

5 In rocking the levers 20 they may be pushed inwardly toward the door 10 to rock the plates 26 forwardly and up onto the front faces of the staves, whereupon downward pull of the levers 20 onto engagement with the bracket 29, causes the springs 19 to be further compressed so as to yieldingly draw the door 10 snugly up against the staves 25 and 16 and bars 32 to effectively close the silo opening 10 and seal the line of contact of the door on the silo members by compression of the felt thereon.

When the levers 20 are engaged in the bracket 29, they lie in a horizontal line with 20 their major portion spaced outwardly from the face of the door 10. One door being above the other in the usual silo construction, these levers 20, so positioned, serve excellently as steps or rungs in a ladder up the side of 25 the silo.

While we have here described and shown our invention in the best form now known to us, it is obvious that structural changes may be made in that form without departing from 30 the spirit of the invention, and we, therefore, do not desire to be limited to that precise form, nor any more than may be required by the following claims.

We claim:

35 1. In a silo, a door, a pair of levers pivoted between their arms spaced apart one from the other on the door and rockably secured thereto, and means separate from the levers permitting said levers to be rocked 40 both normally and parallel to the door.

2. In a silo, a door, a pair of levers pivoted between their arms, spaced apart one from the other on the door and rockably secured thereto, and spring means separate 45 from the levers permitting said levers to be rocked both normally and parallel to the door, and a center bracket adapted to receive and support the ends of said levers therein.

50 3. In a silo door, a clamping device comprising a lever, a bracket, spring means separate from the levers yieldingly supporting said lever in pivoted contact with said bracket, and a center bracket adapted to receive the inner end of the lever therein.

4. In a silo having members about an opening against which a door may be positioned, a door, a bracket near the edge of the door, a lever pivotally carried on the bracket, means permitting the yielding travel of the lever axially of the bracket, a plate on the outer end of the lever, and a center bracket carried on the door adapted to receive the inner end of the lever thereon, whereby the said plate may be placed on the

side of one of said members removed from the door and the lever rocked on said first bracket and brought over and engaged in said center bracket to pull said door compressively against said members by reason of said yielding means. 70

5. In a silo, members along an opening therein, a door adapted to close said opening and lap over said members from the inside of the silo, a pair of horizontally spaced apart lever brackets, a lever pivoted on each of said brackets having a short outer end and a long inner end, spring means yieldingly retaining said levers on said brackets, and a center bracket having a pocket thereon adapted to receive and the inner ends of said levers to retain the levers in a continuous horizontal line. 75

6. In a silo, members along an opening therein, a door adapted to close said opening and lap over said members from the inside of the silo, a pair of horizontally spaced apart lever brackets, a lever pivoted on each of said brackets having a short outer end and a long inner end, spring means yieldingly retaining said levers on said brackets, and a center bracket having a pocket thereon 80

adapted to receive and hold the inner ends of said levers to retain the levers in a continuous horizontal line, and a cam face on the upper part of said center bracket whereby the inner ends of said levers may be slidably guided thereover outwardly from the door and downwardly into said pocket when the short ends of the levers are positioned 85 on the outside of said opening members to yieldingly move the levers outwardly on said lever brackets by overcoming said spring means. 90

7. In a silo, a door, a pair of levers pivoted between their arms spaced apart one from the other on the door and rockably secured thereto, and means permitting said levers to be rocked both normally and parallel to the door, a center bracket on the door and a cam face on said center bracket over which the ends of said levers may be moved. 100

8. In a silo, a door, a pair of levers pivoted between their arms spaced apart one from the other on the door and rockably secured thereto, and means separate from the levers permitting said levers to be rocked both normally and parallel to the door, said means frictionally retaining said levers at selected 110 points of rotation. 115

In testimony whereof we affix our signatures.
